FIG. 7

INVENTOR.
Fred Mathews
BY
Frank D. Harrason
ATTORNEY.

UNITED STATES PATENT OFFICE.

FRED MATHEWS, OF CHICAGO, ILLINOIS.

LATCH FOR AUTOMOBILE-HOODS.

1,368,276.

Specification of Letters Patent. Patented Feb. 15, 1921.

Application filed March 15, 1920. Serial No. 365,708.

To all whom it may concern:

Be it known that I, FRED MATHEWS, a citizen of the United States, residing at Chicago, in the county of Cook and State of Illinois, have invented new and useful Improvements in Latches for Automobile-Hoods, of which the following is a full, clear, and exact description.

My invention relates to means for securing the hoods of automobiles and the like, and particularly latches, which engage their keepers on the inside of the hood, and are operated by handles projecting outside of the same.

15 The object of my invention is to provide a latch of the kind above referred to in which the latch or engaging member is actuated by a handle, projecting outside of the hood, through the medium of devices 20 that throw it into engagement and out of engagement with a snap and whose pivotal connections are moved off center and retained at the limit of their movement by a spring which prevents rattling whether said 25 latch is in engagement with the keeper or disengaged therefrom. This and other objects I accomplish by the means hereinafter fully described, and illustrated in the drawings, in which similar references indicate 30 similar parts and elements.

In the drawings:

Figure 1 is an inside view of a fragment of the hood of an automobile and platform engaged thereby, showing my improvements 35 applied thereto.

Fig. 2 is a transverse section of the same taken on dotted line 2, 2, Fig. 1.

Referring to the drawings A represents a fragment of one hinged side section of the 40 hood, which is adapted when swung down to cover the engine, to engage or rest upon a horizontal platform *a*, which is flanked by the front fender (not shown) in the usual manner.

45 The side section of the hood (hereinafter referred to as the hood) is fastened usually by two of my improved latches located near each end, at a suitable point above the lower edge of the same, in the usual manner, and 50 said hood is provided with a vertical slot *b* out through which the handle 5 of my improved latch projects outward. Just inside of the hood this handle is pivoted by means of a suitable pivotal pin 6, between the two 55 corresponding downwardly extending parallel branches 7, 7, of an inverted U-shaped

sheet metal supporting-frame 25. The edges of these branches at the end of the horizontal portion of the supporting-frame next the hood is provided with lateral lugs 60 8, 8, that are riveted or otherwise fastened to the hood along side of and parallel to slot *b*. These branches 7, 7, project inwardly from the hood and then downwardly.

Inside the hood the handle is provided 65 with a short downward extension, and its lower end is bifurcated by means of a slot 10, that is engaged by an antifriction wheel 11, journaled between the bifurcated end of the upper horizontal arm 12 of the latch 13. 70

This latch consists of a vertically disposed member that connects the said upper arm 12, and a lower horizontally disposed arm 14, and the latch is pivoted by means of a transverse pivotal trunnion 15 at the angle 75 of arm 12 and its vertical member, and the ends of this trunnion 15 extend out through vertical slots 15^a made in the side members of the supporting-frame 7. At the angle or elbow formed at the lower end of its vertical 80 member said latch is provided with a transverse bar 16, the ends of which extend out through segmental slots 17, 17, made in the lower end of the side branches of the supporting-frame 7. These segmental slots are 85 struck from a center farther away from the hood than the pivotal pin 15, so that when handle 5 is depressed and the bifurcated extension engages the antifriction wheel in the adjacent end of upper arm 12 of the 90 latch the latter will move on the axis of trunnion 15 and the engagement of the ends of bar 16 with slot 17 will force the latch upward and the extremity of the arm 14 will move toward the hood and engage the underside of the upper hooked end of a keeper 95 18. This keeper consists of a vertically disposed strip of metal the lower end of which is flanged inward away from the hood and riveted or otherwise fastened to the platform *a*.

100 The latch is, preferably, made of two corresponding strips of metal secured together in any suitable manner and having their upper portions spread or spaced apart 105 so that the antifriction wheel 11 can be journaled between said strips, and so that the lower end of a vertical bolt 19 may be loosely mounted on the trunnion 15, between the same. This bolt extends up through the 110 bend or top portion of the inverted U-shaped supporting-frame 7, and immedi-

ately above said frame a nut 20 engages the screw threaded portion of the bolt, and a washer 21 surrounds the same just above said nut. The upper screw-threaded end of bolt 19 also has a nut 23 mounted thereon, and between nut 23 and washer 21 said bolt is surrounded by a coil expansion spring 24.

In operation, when it is desired to lift the hood, the handle is grasped and lifted up. This, through the engagement of the extension 9 with the upper arm 12 moves the lower arm of the latch away from the keeper, which it thus disengages. As the latch is in the act of disengaging, cross-bar 16, by reason of its engagement with the slots 17, pulls the latch downward against the expansion spring 24. The strength of spring 24 is such that when it is desired to lower the hood, grasping the handle 5 will not cause the latch to start on its locking movement, but when the hood is closed, an extra downward pressure on the handle will cause the latch to snap simultaneously outward and the toe of its lower arm will move upward and engage under the upper hooked end of the keeper as the spring 24 slightly expands. In order to assure the locking engagement of the latch with the keeper in the event the lifting of the handle should accidentally move the lower arm of the latch toward the hood, I have beveled the under edges of arm 14 back from its toe so that should it strike the upper hooked end of the keeper it will be forced away from the keeper and draw the hood toward the same and pass under the hook of the keeper and lock the hood in its downward position firmly against the keeper so that it will not rattle.

40 What I claim as new is:

1. The combination with a movable closure member, a stationary support and a keeper attached to said support, of a handle having a stationary pivot on one side of said support and extending out through a slot therein to the other side of the same, a latch movable on a yielding pivot and having arms projecting from its ends, one of which is adapted to be engaged by said handle and the other to engage and disengage from said keeper.

2. The combination with a movable closure member, a stationary support and a keeper attached to said support, of a handle having a stationary pivot on one side of said support and extending out through a slot therein to the other side of the same having an extension, a latch movable on a yielding pivot and having arms projecting from its ends, one of which is adapted to be engaged by said extension, and the other to engage and disengage from said keeper.

3. The combination with a movable closure member, a stationary support and a keeper attached to said support, of a handle

having a stationary pivot on one side of said support and extending out through a suitable slot therein to the other side of the same, a latch movable on a yielding pivot and actuated by said handle to engage and disengage said keeper and a spring used in conjunction with said yielding pivot.

4. The combination with a movable closure member, a stationary support and a keeper attached to said support, of a handle having a stationary pivot and having an extension, a latch having an upper and a lower arm projecting in the same direction therefrom and which is pivoted at the junction thereof and said upper arm, which latter is engaged by said extension and caused to engage or disengage from said keeper.

5. The combination with a movable closure member, a stationary support and a keeper attached to said support, of a handle having a stationary pivot and having an extension, a latch having an upper and a lower arm projecting in the same direction therefrom and which is provided with a yielding pivot at the junction thereof and said upper arm, which latter is engaged by said extension and caused to engage or disengage from said keeper.

6. The combination with a movable closure member, a stationary support and a keeper attached to said support, of a handle having a stationary pivot and having an extension, a latch having an upper and a lower arm projecting in the same direction therefrom and which is provided with a yielding pivot at the junction thereof and said upper arm, which latter is engaged by said extension and caused to engage or disengage from said keeper, a bolt secured at one end to said yielding pivot, and a coil expansion spring engaged by said bolt.

7. The combination with a movable closure member, a stationary support and a keeper attached to said support, of a supporting-frame comprising two parallel sides connected to said closure member, a handle having a stationary pivot between said sides and extending out through a suitable slot in said closure member to the opposite side of the same, and having a bifurcated extension, a latch having an upper and lower arm projecting in the same direction which is provided with a yielding pivot at the junction of the upper arm therewith, and a cross-bar intersecting the juncture of the lower arm with said latch the ends of which engage slots in said sides.

8. The combination with a movable closure member, a stationary support and a keeper attached to said support, of a supporting-frame comprising two parallel sides connected to said closure member, a handle having a stationary pivot between said sides and extending out through a suitable slot in said closure member to the opposite

side of the same, and having a bifurcated extension, a latch having an upper and lower arm projecting in the same direction which is provided with a pivot at the junction of 5 the upper arm therewith, a bolt secured to and projecting up from said pivot, a coil spring up through which said bolt extends and a nut on the upper end of said bolt, said spring expanding when said extension 10 actuates said latch, and a cross-bar intersecting the juncture of the lower arm with said latch the ends of which engage slots in said sides in said sides.

9. The combination with a movable closure member, a stationary support and a keeper attached to said support, of a supporting-frame comprising two parallel sides connected to said closure member, a handle having a stationary pivot between said sides 20 and extending out through a suitable slot in said closure member to the opposite side of the same, and having a bifurcated extension, a latch having an upper and lower arm projecting in the same direction which is provided with a pivot at the junction of the 25 upper arm therewith, a bolt secured to and projecting up from said pivot, a coil spring up through which said bolt extends and a nut on the upper end of said bolt, said 30 spring expanding when said extension actu-

ates said latch, and a cross-bar intersecting the juncture of the lower arm with said latch the ends of which engage slots in said sides that are curved and which have their ends one on one side and the other on the 35 other side of an imaginary line in alignment with the axis of said bolt.

10. An automobile hood, locking means for said hood located within the same, a keeper and means for raising the hood that 40 actuates said locking devices extending through said hood for engaging said locking devices and move the said locking devices to engage the keeper and move said hood inward.

11. An automobile hood, locking means for said hood located within the same, a keeper and means for raising the hood that actuates said locking devices extending through said hood for engaging said lock- 50 ing devices and move the said locking devices to engage the keeper and move said hood inward against the same.

In witness whereof I have hereunto set my hand this 3rd day of March, 1920.

FRED MATHEWS.
